FRED NEWCOMBE, OF PROVIDENCE, RHODE ISLAND.

LOOSE-REED-ADJUSTING MECHANISM FOR LOOMS.

Application filed March 4, 1927. Serial No. 172,715.

My invention has reference to an improvement in looms and more particularly to an improvement in a loose reed adjusting mechanism for looms.

5 In the usual construction of looms, as heretofore constructed, the reed is fixed in its operative position in the lay, by a reed rest or fastening plate secured to the recessed back portion of the lay. That is to say, the reed 10 is rigidly secured in the lay of the loom, and moves only with the lay.

In the use of looms weaving cloth known to the textile trade as split basket, or similar weaves, it has heretofore been found necessary to use two rigid reeds in the lay of the loom, one back of the other. It has also been found in practice that even by the use of two reeds for this kind of weave the result has been very unsatisfactory, as the warp 20 threads will roll together and knots or unevenness in the warp threads will catch on the reed wires and break the warp threads.

The object of my invention is to improve the construction of a loom weaving split basket or similar weaves, whereby the usual reed rest or fastening plate is removed and the lay of the loom is thereby provided with a reed loosely held in the lay of the loom.

Another object of my invention is to provide the lay of a loom with means for adjusting and limiting the movement of the now loose reed in the lay of the loom.

Another object of my invention is to provide the lay of a loom with means for adjusting the reed lengthwise in the lay of the loom.

A further object of my invention is to simplify the construction of the means for adjusting to limit the swing of the lay and means for adjusting the reed lengthwise in the lay, thereby reducing the cost of constructing said reed controlling and adjusting means to a minimum.

My invention consists in the peculiar and novel construction of elements connected to the lay of a loom, said elements having means for holding a loose reed in the lay of the loom, means for adjusting and limiting the swinging movement of the loose reed in the 45 lay and means for adjusting the reed lengthwise in the lay, said elements having details of construction, as will be more fully set forth hereinafter and claimed.

Figure 1 is a transverse vertical sectional view of the upper part of a loom, showing the 55 lay provided with my improved loose reed adjusting mechanism and with the lay in the forward position.

Figure 2 is an enlarged detail sectional view of the lay in its back position and showing 60 the lay provided with my improved loose reed adjusting mechanism, in section.

Figure 3 is a horizontal sectional view through the reed, taken on line 3, 3, of Figure 1 and looking down in the direction of the 65 arrow *o*, onto the top of the reed adjusting mechanism, with the ends and central portion of the lay broken away, to more clearly show my invention.

Figure 4 is a vertical rear view of Figure 70 3 and showing the reed adjusting mechanism back of the reed.

Figure 5 is an enlarged detail plan view of a portion of one end of the lay, showing that 75 part of the reed adjusting mechanism, partly in section.

Figure 6 is an enlarged detail vertical sectional view taken on line 6, 6, of Figure 5 and looking in the direction of the arrow *p*.

Figure 7 is an enlarged detail vertical 80 sectional view taken on line 7, 7, of Figure 5 and looking in the direction of the arrow *r*, and

Figure 8 is an enlarged detail vertical sectional view taken on line 8, 8, of Figure 5 85 and looking in the direction of the arrow *s*.

In the drawings *a* indicates a portion of an end frame of a loom, *b* the crank shaft, *c* the lay connecting rod, *d* the lay having the downwardly recessed back portion *e* 90 forming a shoulder *f*, *g* the reed, *h* the breast beam, *i*, *i*, the warp threads and *k* the cloth. The top bar *l* of the lay *d* has a recess *m* in which the top of the reed *g* is loosely held by a plate *n*.

In carrying my invention into practice I eliminate the usual reed rest or reed fastening plate, not shown, from the recessed back portion *e* of the lay and substitute in place thereof, my improved loose reed adjusting 100 mechanism *l*, which has the following construction.

2 indicates an L shaped bar having a horizontal member 3 firmly secured to the recessed portion *e* of the lay *d* by screws 4, 4, 105 and 5 a vertical member having a slot 6 ad-

jacent each end, reinforced screw-threaded holes 7, 7, and intermediate guide pin holes 8, 8. This L shaped bar 2 extends lengthwise of the reed *g* and beyond each end of the reed a predetermined distance. A flat reed bar 9 extends practically the length of the reed *g* and fixed to this bar 9 are guide pins 10, 10, which extend through the guide pin holes 8, 8, in the bar 2 and adjustably attach the bar 9 to the bar 2. A screw 11 is screwed through each screw-threaded hole 7 in the L shaped bar 2, the inner ends of the screws 11, 11, engaging with the reed bar 9. Each screw 11 has a nut shaped head 12 and a lock nut 13. A reed lengthwise adjusting member 14 is placed at each end of the L shaped bar 2. Each reed adjusting member 14 has an arm 15 engaging with each outer end of the reed *g* and an arm 16 on which is fixed a screw 17 which extends through the slot 6 in the L shaped bar 2 and the screw 17 has a fastening nut 18 engaging with the bar 2.

By this construction, as shown in Figures 5, 6, 7 and 8, the reed adjusting bar 9 is adjustably attached to the fixed bar 2, by the guide pins 10, 10. The reed adjusting bar 9 is adjusted to control the rearward swinging movement of the reed *g* in the lay *d*, by the screws 11, 11, the shoulder *f* on the lay *d* forms a stop to limit the forward swinging movement of the reed *g*, in the lay *d*, and the reed *g* is adjusted lengthwise by the reed lengthwise adjusting members 14, 14, which may be reversed for adjusting longer reeds. After adjustment the nuts 13, 13, and 18, 18, are tightened, thereby securing the parts in their adjusted positions.

In removing the reed rest or fastening plate, not shown, from under the reed, as heretofore used, a vertical space is gained on the lay of about five eighths of an inch, thus allowing the reed to drop down in this space or in other words, allowing an increase in the length of the reed wires or dents. This dropping down of the reed brings the center portion of the reed wires where they are more flexible and this also brings the center portion of the reed wires on a line with the warp threads, as indicated in dotted lines in Figure 1. By thus positioning the reed wires, knots or irregularities in the warp threads will spring the center portion of the reed wires apart and allow the knots or irregularities to pass through the reed, without breaking the warp threads.

In the operation of my improved loose reed adjusting mechanism for looms, a rearward movement of the lay *d*, will cause the loose reed *g* to swing forward until the bottom of the reed contacts with the stop shoulder *f*, as shown in Figure 2. A forward movement of the lay will cause the reed to move backward as shown in Fig. 1. This loose holding and controlling of the reed in the lay

now allows the reed to ease away from knots and other irregularities in the warp threads, thereby allowing the knots and irregularities on the warp threads to easily pass by the reed wires and through the dents in the reed, 70 without breaking the warp threads.

In fixing up a loom for weaving split basket or similar weaves, as heretofore done, the two reeds are set in the lay one back of the other and offset, so that the reed wires of the back reed are on a center line with the dents in the front reed, the two reeds having the same number of reed wires as used in my single reed for the same purpose. This offsetting of the two reeds is necessary and in 80 hooking the warp threads through these offset dents, it requires approximately six times the time required to hook the warp threads through the dents of a single reed and as it is impossible for the loom fixer to clearly see what he is doing, he is liable to hook the wrong warp threads through the dents, thereby causing a miss weave in the cloth.

Having thus described my invention I claim as new:—

1. In a loom lay, a loose reed in the lay, means for loosely holding the loose reed in the lay whereby the reed has a loose swinging movement in the lay and means for lengthwise adjustment of the loose reed in the lay, for the purpose as described.

2. In a loom lay, a loose reed having a swinging movement in the lay, means for holding the loose reed in the lay, means consisting of a shoulder on the lay to limit the forward movement of the reed and means consisting of a reed adjusting mechanism on the lay, to limit the rearward movement of the reed, for the purpose as described.

3. A loose reed adjusting mechanism for looms having a loose reed, said mechanism comprising a fixed shoulder on the lay, a bar fixed to the lay of the loom, a loose reed adjusting bar adapted to limit the rearward swinging movement of the loose reed, and means on the fixed bar for adjusting the loose reed adjusting bar, for the purpose as described.

4. A loose reed controlling mechanism for looms having a loose reed, said mechanism comprising an L shaped bar fixed to the lay of the loom, a loose reed controlling bar engaging the loose reed and having guide pins extending through the fixed bar, the fixed bar having adjusting screws engaging the loose reed controlling bar, L shaped adjusting members on the fixed bar and engaging the ends of the loose reed, means for locking the adjusting screws, means for adjusting the L shaped adjusting members and means for locking the L shaped adjusting members in their adjusted positions, for the purpose as described.

5. A loom having a lay in which is a trough formed in the top of the lay, said trough hav-

ing a fixed abutment adjacent the raceway of the lay and an oppositely disposed adjustable abutment on the lay, a loose reed in the lay and having a forward and a rearward movement in the lay between the fixed abutment and the adjustable abutment and means on the lay for adjusting the adjustable abut-

ment to vary the width of the trough, whereby the loose movement of the reed is held within the maximum and minimum movements required in the lay. 10

In testimony whereof, I have signed my name to this specification.

FRED NEWCOMBE.
